UNITED STATES PATENT OFFICE

TOM MORRIS, OF GARRISON, WEST VIRGINIA, ASSIGNOR OF ONE-THIRD TO WILLIAM FLOOD AND ONE-THIRD TO JUNIOUS MASON

CAR COUPLER

Application filed April 18, 1929. Serial No. 356,079.

This invention relates to car couplers designed primarily for use in connection with mine cars.

As is well known to those skilled in the art it is necessary that mine cars travel over rough tracks having many short curves. For this reason it has been a difficult matter to devise a coupler by means of which the cars can be coupled automatically while on 10 curved portions of the track.

It has furthermore been difficult to provide a means for uncoupling the cars because the clearances provided at the sides of the track are frequently too small to permit the 15 use of operating levers and similar devices located where they will not interfere with the operation of the end gates of the cars.

Another objection heretofore present in 20 automatic couplers has been the accumulation of small particles of coal in the heads of the couplers which has prevented operation of the parts under all conditions.

It is an object of the present invention to 25 provide a coupler the head of which is mounted to swing laterally, a support being provided therefor whereby the head will be properly guided during such movement.

Another object is to provide a coupling 30 head which can be easily shifted by a foot of a person standing on the rear portion of the coupler at a point where he will not be injured by any parts coming together.

A further object is to provide a coupler 35 having a head so constructed that particles of coal and other substances cannot become lodged therein so as to interfere with the operation of the parts.

A still further object is to provide improved means for attaching the coupler securely to a transverse beam or bolster forming a part of the car structure.

Another object is to provide novel means 45 for locking the knuckle of the coupler in closed position, said means being unaffected in its operation by particles of coal falling on the structure.

With the foregoing and other objects in view which will appear as the description 50 proceeds the invention resides in the combination and arrangement of parts and in the

details of construction hereinafter described and claimed, it being understood that changes in the precise embodiment of the invention herein disclosed may be made within the scope of what is claimed, without departing from the spirit of the invention.

In the accompanying drawings the preferred form of the invention has been shown.

In said drawings,

Figure 1 is a side elevation of the coupler, 60 a portion of the car to which it is attached being shown in section.

Figure 2 is a plan view.

Figure 3 is a section on line 3—3, Figure 65 2, one of the positions of the locking dog being shown by broken lines.

Figure 4 is a horizontal section through the coupler.

Figure 5 is a perspective view of the 70 knuckle.

Referring to the figures by characters of reference, 1 designates a clevis consisting of an upper plate 2 and a lower plate 3 connected by an integral transverse web 4. This clevis is adapted to straddle a cross beam or 75 bolster forming a part of the car structure and can be held thereto by bolts as shown. The upper plate 2 has a forward extension 5 while a broad tongue 6 is extended forwardly from the lower plate 3, this tongue 80 being formed, at its forward end, with an enlargement 7 extending laterally from the tongue and formed with an arcuate transverse slot 8. A pivot pin 9 is adapted to be inserted downwardly through the extension 85 5 and tongue 6 and the slot 8 is concentric with this pin. It is to be understood that all of the parts thus far described, except the pin 9, can be cast in a single piece or, if preferred, can be of separate parts suitably connected.

The head of the coupler includes a lower box-like structure 10 the forward end of which is open and recessed as shown at 11 95 while extending rearwardly from the bottom of this member 10 is an ear 12. The bottom of the member 10 is cut away at the sides to provide outlet openings 13.

The top of the member 10 is covered by a 100 top plate 14 the sides of which are cut away

as at 15. This plate has an ear 16 formed by the rear portion thereof. Plate 14 is secured to the member 10 by means of bolts or the like and one of these bolts, indicated at 17, constitutes the pivot of the movable jaw 18 of the coupler. The movable jaw has a wing or knuckle 20 extending backwardly and laterally therefrom adapted, when the movable jaw 18 is in locking position, to be positioned at one side of a locking dog 21 pivotally mounted in the coupler head on a supporting pin 22 extending transversely.

A housing 23 is formed on or secured to the plate 14 and is adapted to receive the dog 21 when it is raised out of the path of the wing 20. This housing has a longitudinal slot 24 through which extends a shank 25 fixedly connected to and extending upwardly from the dog 21.

The ears 16 and 12 extend between extension 5 and tongue 6 and are provided with openings 26 for the reception of the pin 9. With the coupler head thus connected to the clevis, the bottom member 10 thereof will rest on tongue 6 and its enlarged end 7. A bolt 27 or the like extending downwardly from the member 10 is adapted to slide in the slot 8, the head of this bolt serving to hold the head against upward displacement relative to the enlargement 7.

In practice the head is coupled to the clevis as explained and is thus free to swing laterally about the pin 9, the tongue 6 and its enlargement 7 constituting a support and guide for the head. The movable jaw 18 is normally extended forwardly from the member 10 at which time the wing 20 is located beneath and serves to support the free end of the dog 21. Obviously that portion of the member 10 directly opposite the movable jaw 18 constitutes the usual fixed horn or jaw indicated generally at 28.

When a car equipped with this coupler approaches another car to which it is to be connected, the operator can stand on the clevis back of the pin 9. Either side portion of the enlargement 7 will constitute a foot rest and by placing one foot thereon and pressing therewith against the side of the member 10, the head of the coupler can be shifted laterally so as to approach the coupler on the next car at the proper angle to insure engagement of the jaws on the two couplers. As the forwardly extended movable jaw 18 becomes seated in the end of the coupler head in the path thereof, said jaw 18 will be pressed inwardly so as to cause wing 20 to swing laterally from under the dog 21. Said dog will therefore drop to position in the path of the wing and thereby prevent jaw 18 from swinging open. As both couplers on the two cars operate in the same way and simultaneously the jaws 18 thereof will become interlocked.

By mounting the head of the coupler as described it can be easily shifted to insure op-

eration even though the car may be travelling along a very short curve.

During the travel of a mine car over a stretch of track a considerable quantity of the coal piled thereon will slide off, some of this falling on the the coupler and frequently becoming lodged in the head. In the present instance the coupler is provided with openings 13 and 15 so that particles of coal and other foreign substances can sift through the head. Consequently the head will not become clogged.

The dog 21 has been found superior to an ordinary locking pin for the reason that, because of its size and weight and the extent of the slot 24 through which the shank 25 extends, it becomes practically impossible for any particles of coal or the like to become lodged in the head in such a way as to prevent operation of the dog. Shank 25 affords ample means for lifting the dog when it is desired to uncouple a car and this shank will not stand in the way of end gates nor will it necessitate any increase in the clearance provided at the side of the car or the passage of side levers or other coupler operating means.

What is claimed is:

In a car coupler the combination with a clevis for attachment to the draft gear of a car, and a tongue integral with the bottom portion of the clevis having a free end portion of greater width than the remaining portion, of a coupling head pivotally connected to the clevis and supported by the tongue, the free end portion of the tongue being extended laterally beyond the head under normal conditions, thereby to provide footrests, there being an arcuate slot within the free end portion concentric with the pivot of the coupler head, and means carried by the coupler head for sliding within the slot to limit the swinging movement of the head relative to the clevis.

In testimony that I claim the foregoing as my own, I have hereto affixed my signature.
